TRUING APPARATUS

Lester J. Lalime, Providence, R. I., assignor to
Brown and Sharpe Manufacturing Company,
a corporation of Rhode Island

Application April 25, 1942, Serial No. 440,473

8 Claims. (Cl. 125—11)

The invention relates to grinding machines, and more particularly to a grinding wheel truing apparatus for generating a predetermined form on the operative face of the grinding wheel.

In order to grind or finish certain types of curved surfaces, it is necessary to employ a grinding wheel having the operative face thereof shaped or formed to produce the desired curve. In instances of this type the accuracy and fineness of finish of the ground surface is dependent upon the quality of the grinding wheel employed, and particularly upon the accurate shaping of the formed grinding surface. For precision work in which tolerances of as little as a few ten thousandths of an inch may be permitted, it becomes of the greatest importance to provide truing apparatus capable of shaping the operating surface with precision and accuracy at frequent intervals during the operation of the machine.

It is a principal object of the invention to provide in a grinding wheel truing apparatus having a diamond point truing tool movable for generating an irregular contour on the operative face of a grinding wheel, a novel construction and arrangement of the supporting and actuating mechanism which is capable of providing a rigid support for the diamond point dressing tool, while permitting the same to be moved freely and with the greatest accuracy in accordance with a predetermined pattern of movement.

It is a further object of the invention to provide a novel and improved truing apparatus of the general type comprising a swingable support and a tool holder movable transversely thereon in accordance with the dictation of a templet or form, which is particularly constructed and adapted for power operation to cause the tool to advance along its predetermined path at a constant slow rate, and in accordance with a predetermined truing cycle of operation.

With these and other objects in view as may hereinafter appear, the several features of the invention consist in the devices, combinations and arrangement of parts hereinafter described and claimed, which together with the advantages to be obtained thereby will be readily understood by one skilled in the art from the following description taken in connection with the accompanying drawings, in which Fig. 1 is a view in front elevation of a grinding machine to which applicant's improved wheel truing attachment has been applied; Fig. 2 is a bottom plan view of the diamond tool holder and the slide support for the same in the pivoted tool support; Fig. 3 is a top plan view of the diamond tool holder; Fig. 4

is a somewhat fragmentary view in front elevation illustrating particularly the truing apparatus and its supporting standard mounted on the wheel slide; Fig. 5 is a plan view of substantially the parts shown in Fig. 4; Fig. 6 is an enlarged view partly in section and with the parts broken away in left side elevation to illustrate particularly the wheel truing apparatus, the control dogs for the truing apparatus motor being shown 90° out of position, the true position being shown in Fig. 9; Fig. 7 is a detail view in elevation and taken on the line 7—7 of Fig. 6; Fig. 8 is an enlarged detail view partly in section of the diamond tool holder, its supporting guideway and the former or templet; Fig. 9 is a detail sectional view taken on the line 9—9 of Fig. 7, illustrating particularly the dogs and the switch connections for reversing and for subsequently stopping the truing apparatus motor; and Fig. 10 is a diagram of the electrical operating connections for the machine.

The invention is herein disclosed as embodied in a grinding machine which may be of well known description, comprising a base 10, a work support 12 mounted for reciprocatory movement on ways 14 on the base, a headstock 16 and a footstock 18 carried on the work support 12, a grinding wheel 20, a grinding wheel spindle 22, and wheel spindle carriage 24 carried on ways 26 on the base 10 for moving the grinding wheel toward and away from the work. Power operation of the several supports and cooperating mechanisms is effected by means of several electric motors which include a support motor 28 connected through appropriate gearing to reciprocate the work support 12, a headstock motor 30 for rotating the work, a coolant motor 32 generally indicated at 33 in the electrical diagram, and a wheel spindle motor 34 connected to drive the spindle 22 and grinding wheel 20. The present machine is provided with a cross feed mechanism for moving the grinding wheel to and from the work which may be substantially similar to that shown in the patent to Mathewson and Krause No. 2,165,898, and is therefore not here specifically illustrated.

In carrying out the present invention, applicant provides a wheel truing apparatus adapted for truing or dressing a grinding wheel, the abrading surface of which is of irregular outline in cross section, for the performance of a particular grinding operation. The truing apparatus disclosed in the drawings, is of the general type which comprises a support rotatable about an axis substantially normal to the plane of move-

ment followed by the tool during its traverse of the grinding surface. A truing tool holder is slidably mounted on the support for movement with the support, and for movement radially of the support axis in accordance with the dictation of a relatively stationary templet or former, which causes the tool holder, during the rotational movement of the support about its pivot, to follow a predetermined contour line in shaping the operating surface of the wheel.

In the preferred embodiment of the invention illustrated in the drawings, the truing apparatus is supported on the wheel carriage in such a position that the pivotal axis for the tool holder support extends rearwardly on a line nearly tangential to the upper surface of the grinding wheel, and the tool holder is supported to move in a semi-circular arc over and across the upper edge of the wheel. In this location the truing apparatus does not interfere with other operating parts of the grinding machine, and may be supported permanently in operating position. A hood or casing is provided which serves to enclose the truing apparatus, and to assist in the collection of grinding chips and coolant. In the illustrated construction, coolant is supplied to the point of operation of the truing tool by means of a coolant supply line which extends through the hollow pivot shaft on which the tool holder support is mounted to turn.

In accordance with a feature of the invention, applicant's truing apparatus is arranged to be power operated by means of a slow speed electric motor, and a worm and worm gear connection therefrom which drives the truing tool at a rate of approximately two inches per minute. Electrical operating controls are provided for causing the truing apparatus to operate in accordance with a semi-automatic cycle of operation, in which the truing tool is moved in a semi-circular path from one side of the grinding wheel to the other, and is then returned to starting position. The tool holder support is balanced on its axis by means of a counterweight to avoid variations in the load on the driving connections which might otherwise have some tendency to hurry or to retard the swinging movement of the truing tool holder supported with consequent injurious variation in the rate of feed of the truing tool.

Another feature of the invention consists in the construction and arrangement of the tool holder and its supporting guideway to provide a support of extreme rigidity for the diamond point tool, while at the same time permitting complete freedom of movement of the tool toward and away from the grinding wheel in accordance with the dictation of the templet or former associated therewith.

Applicant's improved wheel truing apparatus comprises a standard 38 mounted on a platform 39 on the wheel spindle carriage 24, and a bracket 40 which is fitted for vertical adjustment in ways 41 in the standard 38. Vertical adjustment of the position of the bracket 40 is obtained by means of an adjusting screw 42 threaded into a nut 43 in the bracket 40 and supported adjacent its upper end in an end thrust bearing 45 carried on a plate 44 secured to the standard 38. A hand wheel 46 secured to the upper end of the adjusting screw 42 provides convenient means for adjusting the vertical position of the tool holder support and bracket 40. The bracket 40 is provided at its rear end with a laterally extending reinforced arm 47 which provides sup-

port for the forward end of a hollow pivot shaft 48 and a former or templet 50 hereinafter to be more fully described. A rearward extension 52 of the bracket 40 provides support for the rear end of the pivot shaft 48, and also for the driving and control mechanism for the truing apparatus.

The pivot shaft 48 is arranged to receive thereon the sleeve hub portion 54 of a swingable tool holder support 56. Two ball bearings 58 carried on the pivot shaft 48 are arranged for engagement within the sleeve hub portion 54 of the tool holder support 56, and serve to provide a sturdy, tight fitting pivotal support for the tool holder support 56. An angular bracket 59 formed on the forward end of the tool holder support 56 has secured thereto a box-like guideway generally designated at 60 to receive a tool holder 64 which is supported therein for sliding movement in a plane transverse to the axis of rotation of the tool holder support 56. The tool holder 64 is provided at its lower end with a vertically extending bore 66 to receive the usual diamond truing tool 68 which is securely held in place by means of two clamping screws 70. There is also provided adjacent the lower end of the tool holder 64, a follower roll 72 which is arranged for engagement with the templet or former 50 carried on the forward end of the bracket 47.

In accordance with a feature of the invention, the guideway 60 and tool holder 64 supported therein are particularly constructed and arranged to provide a frictionless sliding support for the tool holder which will secure a maximum rigidity of support for the truing tool during the truing operation while permitting the tool to be moved in accordance with the dictation of the former or templet as the truing tool support 56 is turned on its axis. The guideway 60 specifically takes the form of an L-shaped plate, which is bolted into an angular bracket formed on the support 56, and has formed on the inner faces thereof two guide surfaces 74 and 76 of the guideway. The remaining two sides of the box-like guideway 60 consists of two plates 78 and 80, the plate 78 having formed on the inner face thereof the guide surface 82, and the plate 80 having formed on the inner surface thereof the guide surface 84. The plates 78 and 80 are supported at the top and bottom respectively between two cover plates 86 and 88 which are rigidly secured to the L-shaped plate forming the body portion of the guideway 60. The plate 78 is held in position by means of a bolt 90 and a nut 92 which are anchored at opposite ends in the plate 78 and in the side of the fixed portion of the housing having the face 74 formed therein. The plate 80 is held in place by means of a bolt 94 and nut 96 which are anchored at opposite ends in the plate 80 and in the side of the L-shaped plate having the face 76 formed therein. The bolts 90 and 94 each have a tightening action to maintain a tight operating fit between the opposed guide surfaces and the tool holder supported therebetween. From an inspection of Fig. 8, it will be noted that two slots 91 and 95 are provided in the tool holder 64 to receive the bolts 90 and 94, so that the tool holder is permitted to move freely in an axial direction with relation thereto.

The left and right sides of the tool holder 64 are provided each with three roller bearings for engagement respectively with the faces 74 and

82 of the guideway. As best shown in Figs. 2, 3 and 8 of the drawings, the tool holder is supported with relation to the left side wall 74 by means of three roller bearings 97, one being provided at the upper end of the tool holder, and two being provided at the lower end of the tool holder. The right side of the tool holder is provided with three roller bearings 98 for engagement with the face plate 82, two roller bearings being provided adjacent the top of the tool holder and one roller bearing being provided adjacent the lower end of the tool holder. The front and rear sides of the tool holder each have mounted thereon two roller bearings designated at 99 and 100 respectively, the roller bearings 99 being provided for engagement with the face 84, and the roller bearings 100 being provided for engagement with the face plate 76.

The tool holder 64 is held with the follower roll 72 in continuous engagement with the former or templet 59 by means of a compression spring 101 which is seated within a downwardly extending bore 102 formed in the upper portion of the tool holder, and engages against the cover plate 86. With the construction and arrangement of the tool holder 64 and guideway 60 above set forth, it will be evident that an extremely rigid support is provided for the diamond tool, which will avoid possible deflection of the tool in any direction from its correct position while permitting the tool to be moved in its guideway substantially without frictional resistance and with exactness in accordance with the dictation of the former 59.

During the truing operation, the tool holder support 56 will rotate through substantially 180° from a position in which the tool holder is located at one side of its axis to a corresponding position in which the tool holder is located at the other side of its axis, and will then rotate in the opposite direction to the initial position. In order that the parts may be properly balanced to insure a continuous even rotational movement of the support 56 for feeding the tool during the truing operation, a counterbalancing weight 103 is secured to the sleeve hub 54 of the support 56, so that the support 56 will be substantially in balance irrespective of its angular position.

In accordance with another feature of the invention, applicant provides power driving means which is adapted when thrown into operation to impart a 180° and return rotational movement to the tool holder support 56 at an extremely slow truing rate of feed to effect the truing or dressing of the wheel. As previously noted, it is of the greatest importance that the dressing tool be advanced at an even rate of feed in order to avoid unevenness or variation in the depth of cut taken by the truing tool, and to avoid roughness of finish of the trued surface which would seriously impair the efficiency of the grinding wheel in operation. The mechanism for imparting the rotational feeding movement to the tool holder support 56 comprises a small synchronous electric motor 104 having a characteristic speed of 75 revolutions per minute. The armature shaft 106 is connected by means of a sleeve joint with a shaft 108 having mounted thereon a worm 110 which meshes with a worm gear 112 secured to a sleeve element 114 which is secured to and forms a rearward extension of the sleeve hub 54 of the tool holder support 56. In the illustrated construction, the gear ratio of worm 110 and worm gear 112 is 75 to one so that the tool holder

support is rotated to advance the tool at the rate of one revolution per minute.

As hereinafter more fully set forth in connection with the electrical diagram, the motor 104 is arranged to be electrically reversed at the end of 180° rotation of the tool holder support 56 by the action of a micro-switch 116, and is subsequently disconnected to render the truing apparatus inoperative after the tool holder support 56 has moved through 180° in the reverse direction by the action of a second micro-switch 118. The switches are rendered operative respectively, by the action of dogs 120 and 122 which are adjustably secured in annular T-shaped tracks formed in the opposite faces of a switch control disk 124 fast on the rearwardly extending sleeve portion 114 of the tool holder support 56. The dogs 120 and 122 are arranged for engagement with rollers 126 and 128 on actuating rocker arms 130 and 132 associated with micro-switches 116 and 118 respectively. Applicant's improved truing attachment is encased within a housing 141 which fits over the tool holder support or arm 56 and the guideway 60, and is fitted at its rear side against sleeve hub 54. A downward extension of the housing 141 encases the counterweight 103.

In accordance with a feature of the present invention, the truing attachment is constructed and arranged to provide means for supplying coolant at the point of contact of the truing tool with the grinding wheel without interfering with the swinging movements of the truing tool holder 64 and support 56 about the pivot shaft 48. In the illustrated construction, the pivot shaft 48 is hollow, and is extended forwardly to a point closely adjacent the upper edge of the grinding wheel, so that coolant passing through the bore in the shaft will be directed onto the grinding wheel immediately adjacent the point of engagement of the truing tool therewith. As best shown in Fig. 6 of the drawings, coolant is supplied under pressure from a reservoir (not shown) in the base of the machine through a flexible hose connection 140 which is connected with the rear end of the hollow shaft 48.

The truing attachment provided with the present machine is arranged to be electrically controlled to operate in accordance with a semi-automatic cycle of operation. The electrical operating connections for the machine including specifically the operating connections for the wheel truing apparatus, will be briefly described in connection with the elementary diagram of the electrical apparatus for driving and for controlling the operation of the machine in Fig. 10. As will be evident from an inspection of this figure, power is supplied through main line connections L₁, L₂, L₃ and L₄ to the wheel spindle motor 34, the wheel slide motor 142, the work support motor 28, the coolant pump motor 32, and the headstock spindle motor 30. For starting and stopping all of these motors, a main relay control switch M is provided having switch contacts across the main line. A secondary relay switch L_E having contacts across the main line is operative to start and stop the coolant pump motor and the headstock spindle motor. The control circuit for the machine includes additionally the directional relay switches F and B for controlling the position of the wheel slide motor, the secondary relay switches RC and WS, manually operable machine main start and stop

switches 144, 146, a wheel slide switch 147, and a grind-true switch 148.

The operation of the several operating controls for the machine above noted, while similar in many respects to the electrical operating controls illustrated in the Patent No. 2,165,898 to Mathewson and Krause, will be briefly described as follows:

The pressing of the main start switch 144 energizes relay M of the main starting switch, thus putting in operation the wheel spindle motor 34 and the work support motor 28. Contact M1—2 closes, forming a holding circuit. Assuming that the grind-true selector switch 148 is in the grind position, a movement of the cross feed hand wheel from its retracted position will act to shift the hand wheel switch 147, causing contact 18—4 to be opened, and contact 3—5 to be closed. For a full disclosure of the hand wheel switch 147 and the actuating connections therefor not here specifically illustrated, reference may be had to the patent to Mathewson and Krause No. 2,165,898, above noted. As will be evident from the elementary diagram, the closing of the switch contact 3—5 causes relay LE to be energized, starting the coolant pump motor 32 and the headstock spindle motor 40. Relay WS remains energized through the operation of a holding circuit having therein WS contact 18—4. Relay RC is energized, closing RC contact 21—22 so that the relay F is energized to close the wheel slide motor forward switch. The wheel slide motor starts, and continues in operation until arrested by the operation of the wheel slide limit switch which moves to open contact 19—24 and to close contact 20—24. Return of the cross feed hand wheel to its retracted position at the completion of the grinding operation, causes the hand wheel switch 147 to be returned to its initial position, opening contact 3—5 and closing contact 18—4. Relay RC is now de-energized, causing RC contact 21—22 to open and RC contact 21—23 to close. Relay B is energized, starting the wheel slide motor which operates to return the wheel slide to its retracted position, at which time the wheel slide limit switch is again shifted to open contact 20—24 and to close contact 19—24. Relay LE is deenergized, stopping the coolant motor 32 and headstock motor 30.

Movement of the grind true switch 148 to the true position serves to render the hand wheel switch 147 inoperative, causes relay WS to be de-energized to prevent forward movement of the wheel slide, and causes relays LE and RC to be energized, thus starting the coolant pump motor and headstock motor.

The truing attachment motor 164 of applicant's improved construction is connected across the control circuit above noted, and is arranged to be controlled by means of a number of switch connections which are operable independently of those above described, and include relay actuated truing motor start switches R and L for starting the truing apparatus respectively to the right and to the left, manual truing apparatus start right and left switches 150, 152, a dog actuated switch 116 for reversing the truing motor at the end of the truing movement to the right, a dog actuated truing motor stop switch 118, and a manually actuated truing motor stop switch 158.

The operation of the truing apparatus may be briefly described as follows: The closing of the truing apparatus start right switch 150 closes contact 35—36 to energize the coil R. Contacts

R3—25 and R30—10 close, starting the truing attachment motor 104 so that the truing tool is moved to the right. Contact R35—37 closes, forming a holding circuit for the relay R. At the end of 180° rotation of the tool holder support 56 and tool holder 64, the dog 120 will engage with the micro-switch lever 132 to open contact 32—39, de-energizing relay R, and at the same time closing contact 32—40 to energize relay L. Contact L34—40 closes, providing a holding circuit for the relay L. Contacts R3—25 and R30—20 open, and contacts L25—10 and L29—39 close, reversing the direction of drive of the truing attachment motor 104. At the completion of 180° movement of the tool holder support 56 in a reverse direction to the left, the dog 122 will be brought into engagement with the actuating arm of micro-switch 118 to open switch contact 32—33 so that relay L is de-energized, contacts L34—40, L25—10 and L29—39 open and the truing apparatus motor 104 stops. The truing motor stop switch 153 is maintained in its stop position. Micro-switch 116 will in the meantime have returned to its initial position as the dog 120 rides off the actuating arm.

It may be noted that applicant's truing attachment for truing formed operating surfaces on grinding wheels may be rendered operative independently of whether the grinding wheel is in an advanced or a retracted position, since the truing attachment is mounted upon the wheel slide and is arranged to engage with the upper side of the grinding wheel, and thus avoids any possibility of interference with work which may be placed in the machine.

It will be understood that the invention is not limited to the specific embodiment shown, and that various deviations may be made therefrom without departing from the spirit and scope of the appended claims.

What is claimed is:

1. A truing apparatus for a grinding machine having a longitudinally movable table and a transversely movable wheel slide comprising a standard on the wheel slide, a bracket adjustable on the standard to adjust the truing apparatus toward and away from the grinding wheel, a support pivotally mounted on the bracket to swing in a circular path, a truing tool holder transversely movable on the support, a former mounted on the bracket to move the holder transversely relative to the support as the support is swung about its pivot to cause the truing tool to produce a predetermined shape on the grinding wheel periphery, power actuated means for swinging the support about its pivot at a slow truing rate which comprises a worm and a worm wheel co-axial with and operatively connected with the support, an electric motor connected to drive the worm reversibly in either direction, and means operative upon movement of the support to a predetermined angular position in one direction to reverse the direction of drive.

2. A truing apparatus for a grinding machine comprising a bracket located on the grinding machine in predetermined relation to the grinding wheel, a support pivotally mounted on the bracket to swing in a circular path, a truing tool holder transversely slidable on the support, means including a former arranged to move the truing tool holder transversely relative to the support as the support is swung about its pivot to cause the truing tool to produce a predetermined shape on the grinding wheel periphery, a slow speed revers-

ible electric motor, a worm and worm wheel connection from the motor for rotating the support, and control means for the motor including a switch and a follower element rendered operative by the rotation of the support, said worm wheel being supported to turn co-axially and as a unit with the support through a predetermined angle to reverse the motor, and a second switch and follower element rendered operative by the return of the support to its initial position to stop the motor.

3. A truing apparatus for a grinding machine comprising a bracket located on the grinding machine in a predetermined position with relation to the grinding wheel, a support pivotally mounted on the bracket to swing about a substantially horizontal axis, a tool holder mounted on the support to swing therewith in a circular path and movable transversely on the support, means including a former and spring means for maintaining the holder in operative relation to the former for controlling the position of the tool holder on the support during the swinging movement of the support to cause the tool to follow a predetermined outline, a counterweight on the support for balancing the support on its axis for any angular position, and power means comprising a slow speed reversible electric motor, and a worm and a worm wheel co-axial with the support pivot connected for rotating the support at a slow truing rate to effect the truing operation.

4. A truing apparatus for a grinding machine having a grinding wheel, a bracket located in a predetermined position with relation to the grinding wheel, a hollow pivot shaft on the bracket extending substantially tangentially from the grinding wheel, an overarm support pivoted to turn on said pivot shaft, a truing tool holder carried on said overarm support for swinging movement therewith and for movement transversely on the support toward and away from the grinding wheel, and means including a former on the bracket for controlling the position of the tool holder on the support during the swinging movement of the support to cause the tool to follow a predetermined outline, power means for rotating the support to effect a truing operation, and a supply connection with said hollow pivot shaft whereby coolant is supplied through said hollow shaft to the point of operation of the truing tool.

5. A truing apparatus for a grinding machine having a grinding wheel rotatable on a horizontal axis, and a grinding wheel carriage, a bracket located on the carriage in a predetermined position with relation to the grinding wheel, a hollow pivot shaft on the bracket extending rearwardly substantially horizontally and tangentially from the grinding wheel, an overarm support pivoted to turn on said pivot shaft, a truing tool holder carried on said overarm support for swinging movement therewith and for movement transversely on the support toward and away from the grinding wheel, and means including a former on the bracket for controlling the position of the tool holder on the support during the swinging movement of the support to cause the tool to follow a predetermined outline, power means for rotating the support to effect a truing operation, and a supply connection with

said hollow pivot shaft whereby coolant is supplied through said hollow shaft to the point of operation of the truing tool.

6. A truing apparatus for a grinding machine comprising a bracket, means to support the bracket on the grinding machine, a pivotally mounted support which is arranged to swing in a circular path, a transversely movable truing tool holder carried on said support, anti-friction roller bearings and guide surfaces cooperating therewith to provide anti-friction sliding support for the truing tool holder on its support, said guide surfaces and roller bearings being disposed in opposed positions longitudinally of and transversely of said path to provide a direct anti-friction support for the truing tool holder in its guided path against deflection in any direction, tightening means for relatively adjusting each of said longitudinally and transversely opposed guide surfaces and the engaged roller bearings to maintain a tight fit therebetween, a former controlling the position of the tool holder on the support during swinging movement of the support to cause the tool to follow a predetermined outline, and yieldable means for maintaining the tool holder in operative relation with the former.

7. A truing apparatus for a grinding machine comprising a bracket located on the grinding machine in predetermined relation to the grinding wheel, a support pivotally mounted on the bracket, a tool holder slidable on the support in a plane intersecting the support axis, a four-sided guideway comprising two pairs of opposed adjustable guide surfaces, anti-friction roller bearing follower elements on the truing tool holder engaging the opposed guide faces, tightening means for said pairs of opposed guide faces for subjecting the tool holder to an engaging pressure therebetween, a former acting on the tool holder to move the holder in said guideway transversely relative to the support as the support is swung about its pivot to cause the truing tool to produce a predetermined shape on the grinding wheel periphery, and yieldable means for maintaining the tool holder in operative relation with the former.

8. In a truing apparatus for a grinding machine having a support and means for effecting movement of the support transversely of the operating face of the grinding wheel, a truing tool holder movable on the support toward and away from the operating surface of the grinding wheel, and means including a former and spring means for maintaining the tool holder in contact with said former for causing the tool during movement of the support to generate a predetermined shape on the operating face of the grinding wheel, the combination of a four-sided guideway on the support comprising two fixed guide surfaces set at right angles to one another and two elements having guide surfaces thereon, each adjustable toward and away from an oppositely facing fixed guide surface, anti-friction roller bearings on the truing tool holder engaging each of said fixed and opposed guide surfaces, and tightening means for moving each of said movable elements and guide faces thereon toward the oppositely facing guide surface for subjecting the tool holder to an engaging pressure therebetween.
